UNITED STATES PATENT OFFICE.

HENRY D. WOODSON, JR., OF FRENIER, LOUISIANA, ASSIGNOR OF FIFTEEN ONE-HUNDREDTHS TO ELIJAH WILSON, OF FRENIER, LOUISIANA.

MACHINE-GUN.

1,174,923.

Specification of Letters Patent.

Patented Mar. 7, 1916.

Application filed July 3, 1915. Serial No. 37,866.

To all whom it may concern:

Be it known that I, HENRY D. WOODSON, a citizen of the United States, residing at Frenier, in the parish of St. John the 5 Baptist and State of Louisiana, have invented certain new and useful Improvements in Machine-Guns; and I do hereby declare the following to be a full, clear, and exact description of the invention, such as will 10 enable others skilled in the art to which it appertains to make and use the same.

The invention relates to improvements in machine guns.

The object of the present invention is to 15 improve the construction of machine guns and to provide a simple, practical, and comparatively inexpensive machine gun equipped with a plurality of separate guns adapted to be fired simultaneously and 20 equipped with breech blocks capable of being simultaneously opened and closed and locked in their closed position.

A further object of the invention is to provide a machine gun of this character designed 25 to be mounted on wheels for use in the field and capable also of being advantageously employed on ships, in forts and various other places.

With these and other objects in view the 30 invention consists in the construction and novel combination and arrangement of parts hereinafter fully described, illustrated in the accompanying drawings and pointed out in the claims hereto appended, it being understood 35 that various changes in the form, proportion and minor details of construction may be resorted to without departing from the spirit or sacrificing any of the advantages of the invention.

40 In the drawings Figure 1 is a plan view of a machine gun constructed in accordance with this invention, Fig. 2 is a front elevation of the same, Fig. 3 is a longitudinal sectional view, Fig. 4 is a rear view. Fig. 5 is 45 a detail view of the cocking mechanism.

Like numerals of reference designate corresponding parts in the several figures of the drawings.

In the accompanying drawing in which is 50 illustrated the preferred embodiment of the invention, 1 designates a series of guns arranged preferably in parallelism and in spaced relation and provided intermediate of their ends with depending lugs 2 which

are secured in sockets 3 of an axle 4 by bolts 55 or other suitable fastening devices. The axle is provided at its ends with spindles 6 arranged in the hubs of carrying wheels 7 and forming trunnions for the entire set of guns to enable the same to be elevated or depressed as required in sighting them. The guns are maintained in proper spaced relation by intermediate and end blocks 6^a and 7^a provided at their opposed end faces with concave surfaces 7^b adapted to fit the guns 60 at opposite sides thereof. The guns are also embraced at the top by arcuate portions 8 of a transverse bar 10 extending across the entire series of guns and connected at intervals with the axle by vertical bolts 9 which pass 70 through the said bar, the spacing blocks and the axle. The bar 10 is provided between the arcuate portions 8 with perforations 11 for the reception of the said bolts 9. The axle is suitably secured to the front end of 75 an approximately triangular support 12 constructed of suitable material and tapered rearwardly as clearly shown in Fig. 1 of the drawings. The tapered support is provided at the rear end with projecting ears or 80 flanges 13 between which is secured a tongue 14. The tongue 14 which is designed to be provided with a double tree and swingle tree not shown, is detachably secured to the flanges by removable bolts 15 and is designed 85 to be disconnected from the support 12 when the machine gun is to be used.

The guns are provided with breech blocks 16 having firing pins 17 and are arranged in and carried by approximately semi-spherical 90 caps hinged at the bottom to the guns at the rear end thereof by a common pintle rod 19 and adapted to swing upwardly and downwardly to close and open the breech blocks but any other suitable form of hinged connection may of course be employed. The caps or holders which are provided at their tops with catches 20 are connected by a transverse bar 21 to enable them to be swung upwardly and downwardly in unison and 95 they are locked in their closed position by a yoke bar 22 extending across the entire series of guns and straddling the upper portions thereof and slidably connected with the supporting means by rods 23 which slide in 100 guides 24 of the axle 4.

The yoke bar or locking bar 22 is provided at intervals with recesses 26 adapted

to receive the rear portions of the guns to enable the yoke or locking bar to straddle the same and engage the said catches whereby the breech blocks and the holders or caps are securely retained in their closed position. The rods 23 and guides 24 are arranged at intervals and are preferably located at opposite sides of the recesses 26 but any other suitable guiding means may be employed 10 and catches may also be provided at opposite sides of the gun as well as at the top if desired.

The breech blocks are simultaneously swung upwardly and downwardly by means 15 of an operating lever 27 connected with the central breech block by means of a link 28 and fulcrumed at its lower end 29. The operating lever 27 is provided with a dog or 20 detent 30 connected with a latch lever 31 and adapted to engage a toothed segment 32. The toothed segment is preferably formed integral with a bracket or support 33 to which the operating lever 27 is pivoted and which is suitably secured to the 25 main frame or support 12 of the gun. The yoke or locking bar is connected with an operating lever 34 fulcrumed at an intermediate point on a suitable bracket or standard 35 having ratchet teeth 36 adapted to be 30 engaged by a pawl or dog 37 carried by the operating lever 34 for securing the latter in its adjustment to hold the locking bar or yoke in an elevated position. One or more 35 operating levers may of course be employed for swinging the breech blocks upwardly and downwardly and for raising and lowering the transverse yoke or locking bar.

The guns are preferably constructed for using center-fire cartridges 38 but any other 40 suitable ammunition may be employed by correspondingly changing the firing mechanism of the gun. The cartridges are exploded by the firing pins which are struck by hammers 39 mounted on an oscillatory rod or member 40 provided at its ends with arms 41 having laterally extending pivots 42 which are mounted in suitable bearings of rearwardly projecting arms 43 of the axle 4. The rod or member 40 is bent 45 at opposite sides of the center to form the arms 41 which are preferably divergent as clearly shown in Fig. 1 to offset the hammers from the terminal pivot portions 42 and the said rod or member 40 is also provided with arms 44 arranged at right angles to the pivot portions 42 and connected with springs 45 adapted to be placed under tension by the oscillatory movement of the rod or member 40 and capable when the latter 50 is released of swinging the hammers forwardly into engagement with the firing pins with sufficient force to explode the cartridges. The springs which are of spiral form are suitably secured at their front ends 55 to the axle but they may be secured to any

other relatively fixed portion of the machine gun as will be readily understood. The oscillatory hammer supporting rod or member is swung rearwardly by means of an operating lever 46 fulcrumed on a bracket or standard 47 and provided with a link 48 having a hook 49 for detachably engaging the rod or member 40. The operating lever 46 is provided with a dog or detent 50 for engaging ratchet teeth 51 of the bracket 55 or standard 47. The oscillatory hammer carrying rod or member is adapted to be locked in a set or cocked position by a pair of catches 52 mounted on a transverse shaft 53 which is journaled in suitable bearings 54 of the main frame or support 12. When the hammer carrying device is engaged by the said catches, the hook link of the cocking or setting lever is disengaged from a loop 55 to enable the springs to swing the 85 hammers forwardly into engagement with the firing pins when the catches are withdrawn by an operating lever or trigger 56 which is connected with the catches 52 by a flexible connection 57 having branches 58. 90 The central gun is provided with front and rear sights 61 and 62 and the machine gun is equipped with a suitable elevating device consisting of a transverse rod or pivot 63, standards 64 and adjusting means 65. The standards 64 which are provided with seats 66 are composed of telescopic sections and the adjusting device 65 which may be of any desired construction consists of a ratchet bar mounted on a lower transverse 100 rod 67 and provided with teeth arranged to engage the pintle rod 63 to vary the relative length of the standards. The upper sections or rods 68 which are slidably upwardly and downwardly in the lower sections of the standard 64 to raise and lower the muzzles of the guns are locked in any adjustment by the ratchet bar 65 which engages the pivot or pintle rod 63 that connects the upper sections 68 of the standard. 110 As the device for supporting the muzzles of the guns at the desired elevation is hingedly connected with the said muzzles it will not be affected by the recoil of the guns when the latter are fired. 115

What is claimed is:

1. A machine gun including an axle, supporting wheels receiving the axle, a series of guns supported by the axle, spacing blocks located at opposite sides of the guns, and a transverse bar arching the guns and secured to the spacing blocks and to the axle. 120

2. A machine gun including an axle provided at intervals with sockets, a series of guns provided with lugs secured in the said 125 sockets, blocks located at opposite sides of the guns and a transverse bar having arched portions extending over the guns and secured to the said blocks.

3. A machine gun, including a series of 130

guns arranged side by side in a transverse row, means for supporting the guns, a transverse row of breech blocks hinged at the bottom and arranged to swing upwardly and downwardly in opening and closing, a transverse member connecting the breech blocks for causing the same to swing in unison, operating means connected with the said member for opening and closing the breech blocks and means for locking the breech blocks in their closed position.

4. A machine gun of the class described including a series of guns arranged side by side, means for supporting the guns, breech blocks for the said guns, a series of holders receiving the breech blocks and hinged on a common axis, a bar or member connecting the holders, and operating means also connected with the holders for opening and closing the breech blocks.

5. A machine gun of the class described including a series of guns, means for supporting the same, a series of breech blocks, hinged on a common axis and provided with catches, a locking member provided with openings to receive the guns and movable into and out of engagement with the catches and means for operating the locking member.

6. A machine gun of the class described including a series of guns, means for supporting the same, a series of breech blocks, hinged on a common axis and provided with catches, and a locking member provided with openings to receive the guns and movable upwardly and downwardly to engage the catches, rods connected with the said member and arranged at intervals and guiding means receiving the rods.

7. A machine gun including a plurality of guns arranged side by side, hinged breech blocks arranged to swing upwardly and downwardly and provided at the top with catches, and a locking member movable upwardly and downwardly and arranged to straddle the guns and engage the said catches to retain the breech blocks in their closed position.

8. A machine gun including a plurality of guns arranged side by side and firing mechanism including a transverse rod or member provided with terminal pivots and having intermediate arms offsetting the body portion of the rod or member from the line of the pivots, hammers carried by the offset portion of the rod or member, springs for actuating the rod or member, a catch for holding the rod or member against the ac-

tion of the spring and a lever or trigger for releasing the rod or member.

9. A machine gun including a plurality of guns arranged side by side and firing mechanism, an oscillatory member provided with a plurality of hammers, yieldable means for actuating the oscillatory member, spaced catches arranged to hold the oscillatory member against the action of the said yieldable means, and a lever connected with the catches for releasing said member.

10. A machine gun including a plurality of guns arranged side by side, breech blocks hinged on a common axis and arranged to swing in unison in their opening and closing movement, operating mechanism for opening and closing the breech blocks, means for securing the breech blocks in their closed position, an oscillatory hammer carrying member arranged to fire the guns simultaneously, a plurality of catches for holding the said member in its cocked or set position, trigger mechanism for releasing the said oscillatory member, and a setting device provided with means for detachably engaging the said member to move the same into engagement with the said catches.

11. A machine gun including a plurality of guns arranged side by side, and an elevating device, common to all the guns including sectional adjustable standards pivotally connected at their upper ends with the guns and means including a substantially vertical ratchet bar for holding the standards in their adjustment.

12. A machine gun including a plurality of guns arranged side by side, and an elevating device, common to all the guns including spaced sectional adjustable standards pivotally connected at their upper ends with the guns and a ratchet bar connected with the sections of the standards for securing the sections in their adjustment.

13. A machine gun including a plurality of guns arranged side by side, and an elevating device common to all of the guns including a pintle rod, standards connected with the pintle rod and composed of adjustable sections, a transverse rod connecting the standards and arranged in spaced relation with the pintle rod, and means for adjustably connecting the said rods.

In testimony whereof I affix my signature in presence of two witnesses.
